(57) **CLAIM**

The ornamental design for an ice fishing depth finder, as shown and described herein.

DESCRIPTION

FIG. 1 is a perspective view of the ice fishing depth finder according to a first embodiment of the invention.

FIG. 2 is a first side view of the ice fishing depth finder of FIG. 1.

FIG. 3 is a second side view of the ice fishing depth finder of FIG. 1.

FIG. 4 is a top view of the ice fishing depth finder of FIG. 1.

FIG. 5 is a bottom view of the ice fishing depth finder of FIG. 1.

FIG. 6 is a front view of the ice fishing depth finder of FIG. 1; and,

FIG. 7 is a back view of the ice fishing depth finder of FIG. 1.

The broken line showing of structural features is included for the purpose of illustrating non-claimed subject matter and forms no part of the claimed design.

It is certified that error appears in the above-identified patent and that said Letters Patent is hereby corrected as shown below:

Title page should be deleted and substitute therefor the attached title page.

Drawings:

Delete drawing sheets 1-2 and substitute therefor consisting of Figs 1-7 as shown on the attached pages 1-3.

Signed and Sealed this

Second Day of November, 2010

David J. Kappos
Director of the United States Patent and Trademark Office
